UNITED STATES PATENT OFFICE

140,756

DESIGN FOR A WHISTLE

Josephus Thompson, Covington, Ohio, assignor of one-third to Grossman Music Company, Cleveland, Ohio, a partnership composed of Julius I. Grossman and Henry S. Grossman

Application June 27, 1944, Serial No. 114,211

Term of patent 7 years

(Cl. D34—15)

To all whom it may concern:

Be it known that I, Josephus Thompson, a citizen of the United States, residing in the city of Covington, county of Miami, and State of Ohio, have invented a new, original, and ornamental Design for a Whistle, of which the following is a specification, reference being had to the accompanying drawing, forming a part thereof.

Figure 1 is an enlarged front elevational view of a whistle showing my new design;

Figure 2 is an enlarged side elevational view; and

Figure 3 is an enlarged cross-sectional view taken along the line 3—3 in Figure 1.

The dominant feature of the instant design resides in the hollow body of substantially circular form, having a rounded peripheral face and plane opposed side walls, said body further having a centrally disposed axially extending opening therethrough, and the plane side walls each having a pair of spaced circular ribs disposed between the edge defining the opening and the rounded peripheral face all as shown in the drawing.

I claim:

The ornamental design for a whistle, substantially as shown and described.

JOSEPHUS THOMPSON.
